CLAIM

The ornamental design for an “automobile,” as shown and described.

DESCRIPTION

FIG. 1 is a front perspective view of the automobile, showing our new design with environmental structure illustrated in broken lines forming no part of the claimed design;

FIG. 2 is a rear perspective view of the automobile;

FIG. 3 is a right side elevational view thereof, both sides being identical thereto;

FIG. 4 is a top plan view thereof;

FIG. 5 is a bottom view thereof;

FIG. 6 is a front elevational view thereof; and,

FIG. 7 is a rear elevational view of the automobile illustrated in FIGS. 1-6.
